UNITED STATES PATENT OFFICE.

EDWIN A. BOARDMAN, OF HOQUIAM, WASHINGTON, ASSIGNOR TO JAMES F. O'BRIEN,
OF SEATTLE, WASHINGTON.

ADJUSTABLE STILT.

Application filed January 28, 1925. Serial No. 5,334.

To all whom it may concern:

Be it known that I, EDWIN A. BOARDMAN, a citizen of the United States, residing at Hoquiam, in the county of Grays Harbor 5 and State of Washington, have invented certain new and useful Improvements in Adjustable Stilts, of which the following is a specification.

My invention relates to stilts and the main 10 object of the invention is to furnish a device whereby the height of the foot rest may be adjusted from the ground into any desired position along the stilt pole.

For this purpose the foot rest is detachable 15 from the pole and has a cleat adapted to engage around the same to obtain a firm grip thereon when pressure is exerted upon the top of the foot rest while if the latter is raised or tilted upwards the grip is released 20 and the foot rest may be shifted along the pole.

In the accompanying drawing, one embodiment of the invention has been illustrated, and

25 Figure 1 is a side elevation of the stilt complete;

Figure 2 is a side elevation and partial section in larger scale of a portion of the stilt; and

30 Figure 3 is a transverse section along line 3—3 of Figure 2.

In the drawing, reference numeral 10 represents the stilt pole which is shown perfectly straight and preferably rectangular 35 in cross section as best seen in Figure 3.

The foot rest is made of a block of wood 11 with a hollowed out or concave top surface 12 and a convex bottom surface 13 running out to a point 14 so that the contour 40 of the foot rest has the appearance of a horn. The inner end of the foot rest is comparatively heavy and has an intermediate clutching rib or ridge 15 adapted to make contact with the adjacent side of the stilt pole 10, the surface diverging upwardly and 45 downwardly from said ridge.

At the inner end on the upper side of the foot rest is secured, by a screw or rivet 16, 50 a strap 9, intended to be laid over the top of the foot of the user and attached to a button 17 near the point 14 on the outer side of the said rest.

A U-shaped cleat 18 is secured by means 55 of rivets 20 or the like on both sides of the foot rest and its transverse portion 19

is spaced some distance from the end portion 15 of the foot rest. The upper edge of the transverse portion 19 of the cleat is preferably turned inward and serrated or formed with teeth, as indicated at 21 in Figure 3. 60 The cleat 18 is slightly inclined upwardly, relative to the foot rest, so that, when pressure is exerted upon the concave upper side 12 of the foot rest by a person standing on the latter, the ridge 15 contacts with the adjacent side of the stilt pole 10 while the end surface of the rest above and below the ridge stands away therefrom. The serrations or teeth 21 are thus caused to grip 65 tightly on the opposite side of the stilt pole and will dig into the same to a certain degree, the pole being thus clutched by and between the teeth and the ridge. In order to hold the rest in place when the stilt is not in use, a spring 22, which may be either a plate or a light rod, has one end driven 70 into the rest, as at 23, while its upper end will constantly press against the adjacent surface of the stilt pole 10 above the cleat 18. 75

By rolling the foot rest 11 upwardly on its ridge 15 against the pressure of the spring 22, the teeth or serrations 21 will disengage the opposite side of the stilt pole so that the foot rest is free to slide up or down along the latter. When a suitable height has been found for the foot rest, the latter is permitted to roll downwardly on its ridge 15 actuated by its weight as well as by the spring 22. The teeth 21 will at the same time obtain a firm grip on the opposite side of the stilt pole so that, when a person puts his foot on the foot rest 11, the grip will be further increased and the foot rest prevented from sliding down the stilt pole 10. 85

Instead of providing teeth directly on the upper edge of the cleat 18 a separate piece of metal may be secured on the inner side of the transverse portion 19 thereof, said piece being furnished with suitable teeth or roughened to obtain a good hold on the surface of the stilt pole. 90

100 It will be evident that the foot rest or stirrup may be varied in shape and made from different kinds of material. As shown in the drawing, the foot rest consists of a block of solid wood but it may also be made from wire or band iron. Instead of the leaf spring 22 shown in the drawing, a coil spring or press button may be employed. 105 The strap 9 when tightened over the 110

wearer's foot will permit him to shift the stirrup or foot rest without getting off the stilt. To do this he will stand on one foot and slightly raise the other one when the 5 teeth 21 will be released and the foot rest drawn up to the desired height. By thereupon standing on the raised foot rest and lifting his first foot, the user may be able to 10 raise the foot rest on the other stilt pole to the same height as the first one. This may be done gradually so that if, for instance, he desires to raise the stirrups or foot rests six 15 inches he may shift them one inch at a time.

This invention is applicable not only to 20 stilts but also to crutches and painter's scaffold or the like where adjustment of the supporting member is desired.

Having thus described the invention, I 25 claim:

- 20 1. A stilt comprising a pole, a foot rest extending from said pole and having its inner pole-engaging end formed with upper and lower inclined faces converging towards the pole and intersecting to provide a fulcrum adapted to engage the pole, and means 25 for adjustably securing said foot rest on the pole, said means including a yoke rigidly united with the foot rest and extending around said pole and having a portion 30 disposed substantially parallel to the upper inclined face with its upper edge adapted to engage the pole at a point above the plane of said fulcrum for biting engagement with the pole when the foot rest is swung downwardly, and resilient means carried by said 35 foot rest and engaging said pole to swing the foot rest downwardly.
2. A stilt comprising a pole, a foot rest extending from said pole and having its inner end formed with upper and lower inclined faces converging towards the pole to 40 provide a fulcrum intermediate its depth

and adapted to contact with the adjacent side of the pole and permit vertical tilting of the foot rest, and means for adjustably securing said foot rest on the pole, said means including a yoke formed from a flat strap extending about the pole and having arms extending upon opposite sides of the foot rest and secured to the sides thereof 45 intermediate its depth, the portion of the yoke at the opposite side of the pole from the foot rest having its upper edge portion provided with a serrated flange extending 50 towards the pole and adapted to be drawn 55 into biting engagement with the side of the pole above the plane of said fulcrum when the foot rest is swung downwardly.

3. A stilt comprising a pole, a foot rest having an arcuate surface adapted to contact with the adjacent side of said pole, means for adjustably securing said foot rest on the pole, said means including a gripping member united with said foot rest and reaching around said pole and a serrated 60 edge on said member adapted to be pressed against the opposite side of said pole, and a spring inserted between said arcuate surface of said member and the side of the pole.

4. A stilt comprising a pole, a foot rest 70 having an arcuate surface adapted to contact with the adjacent side of said pole, means for adjustably securing the foot rest on the pole, a lifting strap on said foot rest, said means including a gripping member 75 united with said foot rest and reaching around said pole and a serrated edge on said member adapted to be pressed against the opposite side of the pole, and a spring inserted between said arcuate surface of said 80 member and the side of the pole.

In testimony whereof I affix my signature.

EDWIN A. BOARDMAN. [L.S.]
